UNITED STATES PATENT OFFICE.

FRANK JUDSON JEWELL, OF ROME, NEW YORK, ASSIGNOR TO FRANK JUDSON JEWELL AND NELSON ADAMS, BOTH OF ROME, NEW YORK, TRADING UNDER THE FIRM-NAME OF BETSON PLASTIC FIRE BRICK CO.

METHOD OF CONSTRUCTING FIRE-BRICK ARCHES.

1,288,015.

Specification of Letters Patent. Patented Dec. 17, 1918.

Application filed October 17, 1918. Serial No. 258,663.

To all whom it may concern:

Be it known that I, FRANK JUDSON JEWELL, a citizen of the United States of America, and resident of Rome, in the 5 county of Oneida and State of New York, have invented a certain new and useful Improvement in Methods of Constructing Fire-Brick Arches, of which the following is a true and exact description, reference being 10 had to the accompanying drawings, which form a part hereof.

My invention relates to the building up of fire brick arches in boiler settings and has for its object to provide a method whereby 15 one piece fire brick arches in such boiler settings can be readily and safely constructed.

Broadly speaking, my new method consists in building up in the space beneath that occupied by the arch to be formed a 20 knockdown false work structure of metal bars or pipes supporting a thin metal sheet having the arched form desired for the bottom of the arch to be formed, compacting upon said arched plate a mass of unburned 25 plastic fire brick material into the form of the desired arch and then subjecting the false work and the arch formed upon it to heat until the fire brick material is converted into fire brick, and finally removing the false 30 work and thin iron plate supporting the arch.

Reference being had to the drawings which illustrate my invention and in which—

35 Figure 1 is a front elevation showing the false work in place between the side walls of the setting and the arch of plastic fire brick material formed upon it.

Fig. 2 is a plan view of the false work, 40 and

Fig. 3 is a detailed view showing a preferred mode of attaching the bars of the false work together.

A A indicates the side walls of the boiler 45 setting, B B, etc., indicate a series of light iron bars or pipes, preferably pipes, which

are given an arched form corresponding to that of the arch to be formed and are supported in place in any convenient way as shown by pipe extensions or legs indicated 50 at B' B'. C C etc., are transversely lying light bars or pipes supported on the arched pipes B and preferably secured thereto by wires as indicated at D, Fig. 3. C' is a light metal plate of sheet iron or fairly heavy tin, 55 which is supported on the bars C and conform to the curvature of the bars B and of the arch to be formed upon it. F, Fig. 1, indicates the arch which I formed of unburned and plastic fire brick material, while 60 compacted together, and into the form desired.

The false work being built up and the arch F of plastic material being formed upon the plate E, as described, heat is applied 65 for the purpose of burning the fire brick material into fire brick. The heat is readily transmitted through the light frame work of the false work and the thin plate supporting the arch, and, of course, should 70 be regulated in the manner well known for the proper burning of fire brick. After the arch is sufficiently burned the false work and thin plate upon which it is built can be readily removed. 75

Having now described my invention, what I claim as new and desire to secure by Letters Patent is:

The method of constructing a one piece fire brick arch, which consists in building 80 a knockdown false work structure of metal bars or pipes supporting a thin metal sheet having the arched form desired for the bottom of the arch, compacting a mass of unburned plastic fire brick material on said 85 arched plate in the form of the desired arch, heating the false work and the arch formed upon it until the fire brick material is converted into fire brick and then removing the false work.

FRANK JUDSON JEWELL.
